(57) **CLAIM**

The ornamental design for a pump adapter, as shown and described.

DESCRIPTION

FIG. 1 is a first perspective view of an pump adapter, according to one preferred embodiment of the invention;

FIG. 2 is a second perspective view of the pump adapter shown in FIG. 1;

FIG. 3 is a first side view of the pump adapter shown in FIG. 1;

FIG. 4 is a second side view of the pump adapter shown in FIG. 1;

FIG. 5 is a bottom view of the pump adapter shown in FIG. 1; FIG. 6 is a top view of the pump adapter shown in FIG. 1; FIG. 7 is a third side view of the pump adapter shown in FIG. 1; and,

FIG. 8 is a fourth side view of the pump adapter shown in FIG. 1.

The broken lines showing portions of the pump adapter are not part of the claimed design.
